UNITED STATES PATENT OFFICE.

GEORGE S. WEINERTH, OF READING, PENNSYLVANIA.

CIRCULAR-KNITTING MACHINE.

1,406,514.

Specification of Letters Patent. Patented Feb. 14, 1922.

Application filed March 17, 1921. Serial No. 453,024.

To all whom it may concern:

Be it known that I, GEORGE S. WEINERTH, a citizen of the United States, residing at Reading, in the county of Berks and State 5 of Pennsylvania, have invented certain new and useful Improvements in Circular-Knitting Machines, of which the following is a specification.

My invention relates to circular knitting 10 machines and my object is to provide improved mechanism whereby a high spliced heel and reenforced sole may be readily provided by the insertion of an additional thread or yarn and a neat and finished appearance insured by the positive engagement 15 of the additional thread or yarn by determined needles only. The invention is fully described in connection with the accompanying drawings and the novel features 20 are pointed out in the claims.

Fig. 1 shows in vertical section, on the line 1—1 of Fig. 2, a portion of a well known type of knitting machine in connection with a preferred embodiment of my 25 invention applied thereto.

Fig. 2 is a sectional plan view of the same on the line 2—2 of Fig. 1.

Fig. 3 is a developed interior view of the cam block indicating the needle courses. 30 Fig. 4 is a view looking in the direction of the arrow 4 in Fig. 1 indicating the thread carrier fingers and differently raised needles.

Fig. 5 is a separate view of the reversely movable side portion of the top center cam 35 and its operating device.

To form a high splice heel or re-enforced foot of a stocking an extra thread is introduced into the regular circular knitting for a part of each circular course. This has 40 been accomplished by raising and lowering the guide finger which carries the extra thread, during successive revolutions of the needle cylinder, so that it will be in position to feed to determined needles only during 45 such revolutions; but the avoidance of any objectionable irregularity in the product calls for a certainty of engagement with the determined needles in each course which is best attained by a proper separation of such 50 needles from the others during their engagement by the reenforcing thread. The main objects of my invention are to provide for effecting such separations and enabling the thread finger to remain in fixed feeding position during the high-splicing operation. 55

In the well known type of machine indicated, the needles employed to engage the extra or reenforcing thread are the short-butt needles 20; and I have provided a special construction of the knitting cams to 60 properly divide them at the yarn feeding point for the receiving of the reenforcing thread, while the regular knitting thread engages all of the needles.

Referring to the drawings the usual right 65 and left stitch cams 10 and 11, the center levelling cam 12, and the needle rest 13, are employed in well known manner, but I have provided a specially constructed and operated top center cam. This comprises 70 a main cam portion 15 and a side portion 16, both of which are radially movable toward and away from the needle cylinder 17, independently of the movement of the entire knitting cam head 18. These cam portions 75 15 and 16 are made to always move in reverse directions, so that only one will project at a time sufficiently to engage the short butt needles 20; the long butt needles 21 always contacting with and being depressed by the main portion 15 which is withdrawn only sufficiently to clear the short butt needles, while the cam portion 16 when in withdrawn position clears both 80 the long and short butts. In Fig. 3 I have indicated in dotted lines the respective paths 21^a and 20^a of the long and short butt needles when the main center cam 15 is withdrawn and the side center cam 16 is projected; showing the depressing of the 85 long butt needles by the main cam portion 15 before the short butt needles are depressed by the side portion 16 thereof, whereby a prolonged feeding elevation of the short butt needles only is secured. The 90 thread guide finger 25 which carries the reenforcing thread is provided as shown with an adjustably set guide eye 26, to permit of locating the thread as close as possible to the short butt needles when it is 100 lowered to operative position as controlled by the adjustable screw 26^a; and it may remain in this fixed position during the re-enforcing operation as its thread cannot be engaged excepting when the main center cam 15 is withdrawn so as to permit the short butt needles to continue in elevated position until they strike the projected side center cam 16. 105

The mechanism for jointly effecting the 110

reverse projecting and withdrawing movements of the top center cam portions 15 and 16 is as follows: The main cam portion 15 is provided with a longitudinal slot 15^a to slidably engage a top guide-rib 18^a on the cam head 18; to which latter it is loosely held by screws 30 so as to permit of a limited radial movement of the cam portion 15 on the head 18. And the cam portion 16 is similarly slidable in a slot 31 (Fig. 2) of the head 18. To provide for imparting simultaneous but reverse movements, of different extent, to the cam portions 15 and 16, a lever 32 is pivoted to the cam head 18 with its longer arm 33 engaged in a slot 16^a of the cam portion 16 and its shorter arm engaged in a slot 15^b of the main cam portion 15; so that movement imparted to one of said cam portions will 20 reversely move the other. As shown such movement is imparted to the cam portion 16 by means of a vertically slidable operating device 40 guided in the cam-head extension block 18^c, and having a wedge-face 41 bearing against the end 16^b of cam portion 16; a spring 42 being arranged to normally retract the latter and to correspondingly project the main cam portion 15, and a spring 43 normally raising said operating device 30 vice 40.

These reverse movements of the cam portions 15, 16 are automatically effected at proper times by a pattern wheel 45, through a lever 46 and connection 47 operating a 35 sliding finger 48 vertically slidable in the frame bracket 49; said finger bearing upon the spring-raised device 40 to depress the latter when the lever 46 is correspondingly swung by the pattern wheel.

40 The thread guide fingers indicated are lowered and raised to operative or inoperative position by automatically operated levers 50, 51 as usual; but such movements of the reenforcing thread finger 25 are not

required or effected in each course of the 45 reenforced portion of the fabric to determine the particular needles to be engaged by its thread, this being determined solely by the elevating of such needles above the others at the engaging point as has been 50 described, with resulting certainty as to uniformity of the product as well as avoidance of the rapidly repeated operation of the needle finger.

What I claim is:

55

1. In combination with a needle cylinder provided with relatively long-butt and short-butt needles and with cam mechanism therefor; a top needle-lowering cam comprising a radially movable central portion and a 60 movable side portion operative with said central portion but in reverse direction thereto.

2. In combination with a needle cylinder provided with relatively long-butt and short-butt needles and with cam mechanism therefor; a top needle-lowering cam comprising a central portion which is radially movable to clear the short-butt needles only, and a side portion operative with said central portion but in reverse direction thereto and sufficiently to clear both long-butt and short-butt needles when in retracted position. 70

3. In combination with a needle cylinder provided with relatively long-butt and short-butt needles and with cam mechanism therefor; a top needle-lowering cam comprising a radially movable central portion and a movable side portion operative with said central portion but in reverse direction 75 thereto; and a reenforcing-thread carrier-finger fixedly arranged to supply determined needles during the withdrawal of said central cam portion and simultaneous projection of said movable side cam portion. 80 85

In testimony whereof I affix my signature.

GEO. S. WEINERTH.
